[57] ABSTRACT

A dispensing device comprising a pair of buckets symmetrically mounted so as to be movable between emptying and filling positions. Additive metering means operated by the movement of the buckets to supply additive to a trough into which the buckets discharge.

6 Claims, 2 Drawing Figures

PATENTED JUN 25 1974

3,818,925

FIG. 1.

FIG. 2.

ADDITIVE MEASURING DEVICE

This invention has been devised to provide a dispensing device for adding a measured quantity of soluble material into a water reservoir. The invention has been primarily devised for use with a stock water trough.

Often, the most readily available supply of stock drinking water has undesirable characteristics, it may, for example, in its natural condition cause illness or oversupply of some earth element to stock. In some instances continued intake of such water may cause the death of the animals. Most deficiencies which exist in naturally occurring water can be offset or overcome by the introduction of a controlled quantity of additive into the water. It is for the foregoing reason that the present invention has been developed.

Accordingly, this invention provides a dispensing device comprising a support frame, a symmetrical bucket assembly, mounting means centrally and pivotally connecting the bucket assembly to the support frame, stop means to limit the pivotal movement of the bucket assembly in one direction at a first location where the portions of the bucket assembly on each side of the pivotal axis are respectively located adjacent a supply for a first liquid and an emptying position and in the opposite direction at a second location where the reverse conditions apply, metering means for an additive, said means being mounted on said frame and including a housing with two parts and a rotatable member arranged there-between, said rotatable member having a measuring chamber with port means alternately alignable during rotation of said rotatable member with one of said housing ports adapted for connection to a supply of said additive and alternately with the other of said ports forming an outlet into said bucket assembly, and drive means to rotate said rotatable member powered by the pivotal movement of the bucket assembly between the first and second locations as a result of alternate filling and emptying of the bucket assembly portions.

The invention in a presently preferred form is illustrated in the accompanying drawings in which:

FIG. 1 is a perspective view of an assembled dispensing device, and

FIG. 2 is an exploded perspective view of the additive metering means of the device of FIG. 1.

A symmetrical bucket assembly 1 comprising a pair of identical buckets 2 and 3 is centrally supported by a shaft 4 mounted in bearings 5 on a metal frame 6 adapted to lie across a stock feed trough 7 shown in broken outline. From FIG. 1 it will be seen that the buckets are generally triangular in shape and (in the raised filling position, see bucket 2) the top edge of the bucket is horizontal. Bucket 3 in FIG. 1 has its bottom horizontal (or slightly angled down) the bucket is thus in an emptying position.

Stops 8 (preferably resilient) on the frame 6 locate the buckets 2 and 3 in the lowered emptying locations.

The buckets 2 and 3 are adapted (on pivotal movement) to be alternately located below a water inflow X in FIG. 1. A known type of float controlled valve operating from the surface of the water in the trough 7 is used to control the flow X. Also mounted on the frame 6 are baffle assemblies 9 each comprising a support bar 10 on which is mounted a curved plate 11. The plate 11 may be flat if desired. The plates 11 are provided

with slots 12 to allow them to be movable up and down. Locking screws 13 are used to secure the plates 11 to the bars 10. The plates 11 are spaced from the front edges 2a and 3a of the buckets 2 and 3, which are substantially parallel to the pivotal axis of shaft 4, and regulate the flow of water out of the buckets 2 and 3 over the said edges as the buckets are lowered to the emptying locations.

A metering device 14 (see FIG. 2 where the device 14 is for convenience inverted from the operative position shown in FIG. 1) is also mounted on the frame 6. The device 14 comprises a housing 15 having a mounting plate 16 and a conical bore 17. Diametrically disposed on the housing 15 there are two parts formed by the liquid inlet and outlet pipes 18 and 19. A conical nosed rotatable member or rotor 20 containing a measuring chamber fits, in a fluid tight manner, in bore 17. The small end of the rotor 20 projects from the housing and has a ratchet wheel 21 fixed to it. There is a diametrical port 22 at one side of the rotor 20 leading into the measuring chamber and being, positioned to alternately align with the pipes 18 and 19 during rotation of the rotor. The rotor 20 is also axially bored leading into the measuring chamber as at 23 to receive a sliding plunger 24 having finger grips 25. An O-ring 29 is disposed in the bore 23 to seal on the periphery of plunger 24 and hold it in a selected axial location. The size of the measuring chamber can be varied at will by introducing plunger 24 a desired amount into the rotor 20. Sealing engagement between the rotor 20 and the housing bore 17 is achieved by spring finger 25a which is fixed to frame 6 and presses on the outer end of rotor 20.

The rotor 20 is rotated by a ratchet pawl 26 pivotally mounted on the bucket assembly as at 27 and engageable with the teeth of ratchet wheel 21 when the bucket assembly is in the position shown in FIG. 1. When the bucket assembly pivots to empty bucket 2 the pawl 26 is raised by engagement with eccentrically mounted block 28. By varying the position of block 28 the pawl 26 can be arranged to provide a partial turn of the rotor 20 equivalent to one or several tooth pitches of the pawl 21. In this way the times at which pipes 18 and 19 respectively are in communication with the port 22 can be regulated.

The provision of plunger 24 is optional, it is obvious that rotors of different chamber size could be fitted to provide the same effect as is achieved by the use of plunger 24.

I claim:

1. A dispensing device comprising a support frame, a symmetrical bucket assembly, a mounting means centrally and pivotally connecting the bucket assembly to the support frame, stop means to limit the pivotal movement of the bucket assembly in one direction at a first location where the portions of the bucket assembly on each side of the pivotal axis are respectively located adjacent a supply for a first liquid and an emptying position and in the opposite direction at a second location where the reverse conditions apply, metering means for an additive, said means being mounted on said frame and including a housing with two ports and a rotatable member arranged therebetween, said rotatable member having a measuring chamber with port means alternately alignable during rotation of said rotatable member with one of said ports adapted for connection to a supply of said additive and alternately with the other of said ports forming an outlet into said

bucket assembly, and drive means to rotate said rotatable member powered by the pivotal movement of the bucket assembly between the first and second locations as a result of alternate filling and emptying of the bucket assembly portions.

2. The dispensing device claimed in claim 1 wherein the bucket assembly comprises two buckets disposed one on either side of the pivotal axis and each having a triangular cross-sectional shape, one edge of each triangular bucket lying substantially parallel to the pivotal axis and providing a lip over which liquid from the bucket discharges, and including adjustable baffle means mounted in front of said lips to regulate the flow of liquid from the bucket portions.

3. The dispensing device of claim 1 wherein the metering device housing has a conical bore and the rotatable member is correspondingly conically shaped and

is resiliently held in sealing engagement with the bore, the thinner end of said rotatable member having a ratchet wheel fixed to it for cooperation with a ratchet pawl pivotally mounted on the bucket assembly.

5. The dispensing device of claim 3 including adjustable stop means whereby the position of engagement of the pawl with the ratchet wheel is made adjustable to regulate the amount of rotation of the rotor for each pivotal movement to and fro of the bucket assembly.

10 6. The dispensing device of claim 1 wherein the measuring chamber in the rotatable member is variable in size.

15 7. The dispensing device of claim 1 wherein the rotatable member includes a slidible plunger movable into and out of said member to vary the size of said measuring chamber.
